UNITED STATES PATENT OFFICE

FREDERICK ASSHETON TAYLOR, OF TADWORTH, ENGLAND

WINDSCREEN

Application filed January 9, 1930, Serial No. 419,476, and in Great Britain January 21, 1929.

This invention relates to draught, dust or like deflecting screens for vehicles, ships or the like and more particularly to screens of the clear vision gap type.

In the specification of prior British Patent No. 224,381 are described and shown various embodiments of such screens which include three parallel planes, one of which is longitudinally spaced from the other two to form a clear vision gap.

One object of the invention is to provide a simpler and more practical construction of screen which is equally efficacious in operation.

15 A further object of the invention is to reduce the depth of the screen from front to rear as much as possible.

According to one feature of the present invention the windscreens comprises a pair of spaced parallel planes inclined rearwardly from the gap, supports holding the planes from relative angular displacement, means forming with said planes a channel open only at opposite ends and a third plane disposed 20 at an angle of less than 180° relatively to the rear of the pair of planes and located with that edge forming one boundary of the gap lying outside the channel but so that if extended the plane would pass into the channel.

30 A further feature of the invention resides in an upper panel unit comprising a pair of spaced rearwardly inclined parallel planes rigidly supported against relative angular displacement and plates closing the lateral spaces between the planes, the said unit being adapted to be applied to a windscreens having a lower panel arranged with its upper horizontal edge below the line of sight 35 of the driver so as to form between the planes and the rear face of the lower panel an angle of less than 180° to provide a horizontal clear vision gap between the panels and with the plane of the lower panel lying 40 between the spaced planes.

The preferred construction comprises a box like structure having a lower panel on one face, an upper panel on the same face projecting forwardly of the plane of the lower panel at an inclination of less than 90° there- 50 to and vertically spaced therefrom, a rear upper panel lying parallel to the front upper panel and wholly within the box like structure and above the lower panel and lateral panels at the sides forming closure members 55 against entry of lateral air currents into said structure.

The gap may be varied in depth by movement of the lower panel in its own plane with or without angular movement thereof and/or 60 by displacement of the rear upper panel or plane in its own plane.

In order to limit the size of liquid globules which may adhere to the bottom edge of the outer of the pair of planes, the said edge is 65 preferably reduced in cross section for example by the provision of a channel tapering outwardly and which in the case of a substantially horizontal clear vision gap may be formed integrally with and below a gutter 70 element arranged on the lower edge of the upper inclined panel.

The invention will be hereinafter more particularly described with reference to the accompanying drawing showing the application of the windscreens to a motor vehicle and in which:

Fig. 1 is a perspective view of the improved windscreens.

Fig. 2 is a vertical transverse section 80 thereof.

Fig. 3 is a vertical transverse section of a modified form.

Fig. 4 is a detail.

Referring to the drawing, the windscreens 85 comprises a lower panel 1, the upper edge of which is located below the line of sight of the driver of the vehicle. Arranged above the panel 1 is a pair of parallel spaced planes 2, 3, which are mounted in a frame work 4 90

so as to be held from relative angular displacement.

The relative disposition of the parallel spaced planes 2, 3, and the lower panel 1 is such that the angle p (Fig. 2) between the rear face of the panel 1 and the rear plane 3 is less than 180° . While the panel 1 has been shown in Figs. 1 and 3 as lying in a substantially vertical plane it is to be understood that it may be inclined to the vertical as represented by the dotted line positions 31, 41, 51, in Fig. 2. Further, the arrangement of the upper edge of the lower panel 1, 31, 41, 51, is such that its plane would pass between the spaced planes 2, 3, but in its normal position the upper edge of the panel 1 lies below the lower edges of the planes 2, 3 to form a clear vision gap 5.

In order to prevent the entry of lateral air currents into the screen the same is provided with side plates 6 and 7 which at their upper ends are extended to form lateral closure members of the space between the planes 2, 3. In this manner the space between the said planes 2, 3 forms a channel which is open only at the opposite ends in the construction illustrated at the top and bottom.

In order to obtain the efficacious operation of the screen as hereinafter described, it is preferred that the upper front plane 2 projects above the horizontal through the upper edge of the plane 3 by a distance e which is at least equal to half the perpendicular distance a between the planes 2, 3. This results in the creation of a partial vacuum behind plane 2 upon movement of the vehicle in a forward direction which aids in creating flow of air upwardly through the channel formed between planes 2 and 3 and the lateral planes 6 and 7. The fact that plane 2 projects above plane 3 substantially prevents the passage of rain downwardly into this channel.

The depth of the gap 5 may be varied, for example as shown in Fig. 3 either by forming the rear upper plane 3 so as to be slidable in its own plane into the position shown at 23 so as to meet the upper edge of the panel 1. The lower panel 1 may also be vertically adjustable from its normal position shown in full in Fig. 3 to the dotted positions shown at 11 or 21. In the position denoted by 11 the panel 1 virtually closes the clear sight gap and in the position 21 the panel 1 is lowered sufficiently to allow a ventilating current of air to pass through the gap into the inside of the vehicle.

In addition to the vertical displacement of the panel 1, it may be arranged to pivot when in any of the positions 1, 11, 21, about a pivot 8 so as to be angularly displaceable along the arcs b , c , and d shown in Fig. 3.

To lead off any moisture tending to collect at the lower edge of the panel 2 a gutter 9 is preferably provided which conveys collected moisture laterally to the screen. In order,

further, to limit the size of the globules which collect on the bottom edge of the front plane 2, the said edge is preferably formed so as to taper outwardly as shown at 10 so as to form an acute angled edge. As shown in Fig. 4 the gutter 9 and edge 10 may be formed integrally from one metal member which is secured to or forms parts of a channel member 12 arranged around the lower edge of the plane 2.

From the above it is obvious that the screen in the preferred construction comprises a box like structure having a lower panel 1, an inclined upper panel 2, a parallel rear inclined panel 3 which lies within the box structure and laterally disposed members 6 and 7 which prevent the entry of lateral air currents into the box structure. The frame 4 of the box structure may be formed in any desired manner, for example of wood or metal or of both substances.

It is also obvious that the upper panel unit comprising the planes 2 and 3 and the lateral plates 6, 7 may be applied as a unit to an existing windscreens having a lower panel 1 the said upper panel unit replacing the normal upper portion of the screen.

The operation of the screen is such as to provide, during relative movement of the vehicle and an air current, an upward flow of air through the space between the planes 2, 3 so that any dust, moisture, or the like carried by the air current moves across the gap without allowing the same to enter into the interior of the screen. There is further a suction effect produced by this air current between the lower edge of the rear panel and the upper edge of the lower panel which causes air to be circulated from the interior of the vehicle outwardly through the space between the planes 2 and 3.

When the vehicle is stationary there is a tendency for rain to flow down the upper surface of the plane 3 and fall off the lower edge thereof into the interior of the vehicle. In order to prevent any inconvenience caused thereby a shield member is preferably provided as shown at 13 which extends inwardly beyond the edge of the plane 3, the shield 13 being preferably arched and forming a gap such as 14 to allow the water to be led away.

It is of course obvious that the panels instead of being plane as illustrated may be curved from side to side. Further, if desired, part only of the windscreens may be constructed in the manner illustrated.

Each or any of the panels may be of clear glass or of other translucent or transparent material or they may be tinted or otherwise treated so as to form a protection against the glare due to the rays of the sun, headlights or the like. For example, the front upper panel 2 is preferably of tinted glass which forms a visor against light rays against which pro-

tection may be obtained if necessary by slight raising of the line of sight.

In addition to or instead of the shield member 13, the lower edge of the rear inclined plane 3 may be provided with a gutter for leading away accumulated water which may be constructed in the same manner as the gutter 9, 10 or otherwise, suitable conduits being provided at opposite sides of the plane 3 to 10 convey the water to the exterior of the screen and/or vehicle.

In such a case those parts of the lateral plates 6, 7 lying outside the channel formed by the planes 2, 3 may be dispensed with or 15 modified and may, in fact, be replaced by existing parts of the vehicle structure such as the doors or the like.

What I claim is:—

1. A windscreen of the clear vision gap type 20 comprising a lower panel unit consisting of a panel having its upper edge forming the lower boundary of a clear vision gap and an upper panel unit comprising a pair of spaced parallel planes disposed at an angle of less 25 than 180° relatively to the rear face of said lower panel and with their lower edges spaced above said boundary edge to form an upper boundary edge, the plane of said lower panel lying between said spaced planes, supports holding said planes from relative angular displacement, and lateral panels forming together with said planes a straight channel of uniform cross-section open only at its upper and lower ends so as to provide an unre- 30 stricted passageway for the flow of air, the lower edge of the front plane of said spaced parallel planes being reduced in thickness relatively to the thickness of said plane so as to prevent the accumulation of large drops 35 of water at the last-mentioned edge.

2. A windscreen of the clear vision gap type comprising a lower panel unit consisting of a panel having its upper edge forming the lower boundary of a clear vision gap and an upper panel unit comprising a pair of spaced parallel planes disposed at an angle of less 45 than 180° relatively to the rear face of said lower panel and with their lower edges spaced above said boundary edge to form an upper boundary edge, the plane of said lower panel lying between said spaced planes, supports holding said planes from relative angular displacement, lateral panels forming together with said planes a straight channel 50 of uniform cross-section, open only at its upper and lower ends so as to provide an unre- stricted passageway for the flow of air, an out- 55 wardly tapering member arranged on the lower edge of the front plane of said spaced parallel planes so as to prevent the accumu- 60 lation of large drops of water at the last-mentioned edge and a gutter member ar- ranged above and formed integrally with said tapering member for collecting water run- 65 ning downwardly on said last-mentioned

plane and thus preventing water from reaching the lower edge thereof.

3. A wind screen for a vehicle comprising side members, a lower panel mounted between said side members at an angle to the horizontal, and a plurality of horizontally displaced upper panels held by said side members in fixed parallel relationship, said lower panel having an upper free edge, said upper panels having free upper and lower edges, 75 the upper edge of the lower panel being normally below the lower edges of the upper panels to provide a clear vision gap, said upper panels being inclined rearwardly with respect to said lower panel, one of said upper panels being disposed vertically above the lower panel and one of said upper panels being disposed behind the lower panel, whereby the vertical projection of the lower 80 panel passes between the lower edges of the upper panels, the upper panels providing a passageway of undiminished cross-sectional area having a lower inlet opening normally above the upper edge of the lower panel and an outlet opening above the inlet opening. 85

4. A wind screen for a vehicle comprising side members, a lower panel mounted between said side members at an angle to the horizontal, and a plurality of horizontally displaced upper panels held by said side members in fixed relationship, said lower panel having an upper free edge, said upper panels having free upper and lower edges, 90 the upper edge of the lower panel being normally below the lower edges of the upper panels to provide a clear vision gap, said upper panels being inclined rearwardly with respect to said lower panel, one of said upper panels being disposed vertically above the lower panel and one of said upper panels being disposed behind the lower panel, whereby the vertical projection of the lower 95 panel passes between the lower edges of the upper panels, the upper panels providing a passageway of undiminished cross-sectional area having a lower inlet opening normally above the upper edge of the lower panel and an outlet opening above the inlet opening, 100

5. A wind screen for a vehicle comprising side members, a lower panel mounted between said side members at an angle to the horizontal, and a plurality of horizontally displaced upper panels held by said side members in fixed parallel relationship, said lower panel having an upper free edge, said upper panels having free upper and lower edges, the upper edge of the lower panel being normally below the lower edges of the upper panels to provide a clear vision gap, said upper panels being inclined rearwardly with respect to said lower panel, one of said upper panels being disposed vertically above

the lower panel and one of said upper panels being disposed behind the lower panel, whereby the vertical projection of the lower panel passes between the lower edges of the upper panels, the upper panels providing a passageway of undiminished cross-sectional area having a lower inlet opening normally above the upper edge of the lower panel and an outlet opening above the inlet opening, and the forwardly disposed upper panel extending higher than the rearwardly disposed upper panel.
